UNITED STATES PATENT OFFICE.

ERNEST H. JACOBS, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

SWITCH.

Application filed April 14, 1919. Serial No. 289,922.

To all whom it may concern:

Be it known that I, ERNEST H. JACOBS, a citizen of the United States, residing at Chicago, in the county of Cook and State of Illinois, have invented a certain new and useful Improvement in Switches, of which the following is a full, clear, concise, and exact description, reference being had to the accompanying drawings, forming a part of this specification.

The subject matter of this invention is an electrical switch.

Switches for opening and closing electrical circuits have heretofore in the art been subject to the general defect of imperfect contact; only a portion of the material—frequently insufficient to prevent overheating—being employed in conducting current.

It has been customary heretofore in the art to hold the switch blades together and in contact with the stationary terminals by either wedging the blades between a pair of spring fingers; employing a number of bolt and spring washer connections arranged adjacent the opposite edges of the terminal; or by slotting the terminal to receive the binding bolt when the switch is closed as well understood by those skilled in the art. In the first instance the very action of wedging drives the fingers apart so that imperfect contact is obtained. I have observed that the arrangement of spring washers adjacent the opposite edges of the terminal is highly unsatisfactory, the tendency of the blades toward spreading within the contacting area under such conditions resulting in imperfect contact. Slotting the terminals to receive the binding bolt not only involves alteration of the terminal, but decreases the relative contacting surface of the switch.

It is now common practice to provide locking mechanisms in connection with such switches to prevent the accidental moving of the movable switch member from its desired position as might result from a variety of causes first of which is a heavy flow of current. A disconnecting switch should not be opened under load. If blown open by an overload it is in danger of being destroyed and also of developing a serious fault either to ground or across phases.

According to my present invention I provide an improved form of lock, which, while it is particularly valuable in switches

of the floating blade type for disconnect purposes is not to be limited to this particular type of switches. While I have shown the lock as applied to an indoor switch of low voltage, I do not wish to limit the invention to this type or form. The preferred form of the lock is characterized by an eye for manipulating both the lock and the switch, which eye extends out beyond the ends of the blades and is pivoted on the ends of the blades and it has a bolt lying between the outer ends of the blades for engaging the outer edge of the outer contact terminal.

The present invention aims to provide an improved form of switch structure in which a uniform spring pressure is maintained upon the blade or blades of the switch over substantially the entire contacting area thereof without slotting or otherwise altering the terminal. This I secure preferably by a spring clip which extends across the width of the outer or free terminal, lying outside of the blades and presses upon the blades along the central area of their contact with the contact of the switch. This spring clip is held by bolts which also serve to anchor the clip to the blades.

The present invention aims further to provide a locking switch wherein the switch blades are floating relative to the locking mechanism; the contracting area of the switch being the only portion wherein the blade or blades are clamped or bound together.

A still further aim of the present invention is the provision of a switch of simple, durable and reliable construction providing maximum positive contacting surfaces. To this end I have provided means whereby the bus bars of the circuit may be utilized as the terminals of the switch, independent terminal lugs and the like being thereby dispensed with.

Other aims of my invention not hereinbefore set forth will appear from the following detailed description and the claims taken with an inspection of the accompanying drawings in which:

Figure 1 is a side elevational view of a switch constructed in accordance with the teachings of my invention;

Figure 2 is a front elevational view of the same;

Figure 3 is an enlarged fragmentary sec-

tional view taken on the line 3—3 of Figure 1; and

Figure 4 is a horizontal sectional view taken on the line 4—4 of Figure 1.

5 The form of switch shown comprises two independent switches 1 and 2, the detailed construction of each of which is the same, so that a description of one will suffice for both.

10 The movable part of the switch 2 comprises blades 3, 4, 5 and 6 arranged in pairs as shown in Figure 2. The blades 3 and 4 are clamped at one end to a stationary hinge terminal 7 by means of a bolt 8 and a pair of spring washers 9 and 10 which maintain a uniform spring pressure upon the blades 3 and 4 to hold them against the sides of the terminal 7. The blades 5 and 6 are clamped in a similar manner to a stationary hinge terminal 11 by means of a bolt 12 and a pair of spring washers 13 and 14.

15 Each of the terminals 7 and 11 comprises a plurality of bus bars, the number of which may be varied according to the size of the bus bars themselves and the capacity of the switch. These bus bars extend thru the base board 15—preferably formed of slate, marble or the like as is usual in switchboard construction—and are arranged and securely clamped by suitable bolts 16 as shown in Figure 4 to the bus bars 17, which bus bars 17 are of the usual type provided as a permanent installation in circuits of this character.

20 The terminals 7 and 11, each of which comprises a pair of bus bars extending thru the base board 15 in parallel spaced relation are maintained securely in place relative to the base board by angle pieces 18 and 19 bolted thereto, these angle pieces being in turn bolted to the base board as shown in Figure 4.

25 This feature of forming the switch terminals of short lengths of bus bars is a feature of great importance. Heretofore it has been customary to form the switch terminals of cast lugs. This has always necessitated an additional joint, usually a solder joint, which is difficult and expensive to make and which usually proves unsatisfactory. By my invention the extra joint is eliminated and a better connection is made. The height of the terminals can be 30 readily adjusted and the spacing can be controlled to suit the conditions. Less material need be carried in stock and yet any requirement can be met.

35 Each of the upper switch terminals 20 and 21 comprises a plurality of bus bars arranged in pairs substantially as described in connection with the terminals 7 and 11, the number of bus bars forming each of the terminals 20 and 21 being immaterial, as 40 this number may be varied to suit different

conditions. The bus bars forming the terminals 20 and 21 extend thru the base board 15 and are arranged and securely clamped by means of bolts 22 to the bus bars 38 substantially as shown in connection 45 with the terminals 7 and 11. The terminals 20 and 21 are maintained securely in place relative to the base board 15 by means of angle pieces 23 and 24 bolted thereto, which angle pieces are securely bolted to the base board 15 as shown in Figure 1. The outer ends of the terminals 20 and 21 may be suitably beveled to give a finished appearance and to facilitate closing of the switch. Where the switch is to serve for reversing 50 connections, another set of terminals (not shown) may be provided beneath the terminals 7 and 11 for co-operation with the blades 3, 4, 5 and 6 upon movement of the blades substantially 180° about the bolts 8 and 12.

55 The lower edge of the base board 15 is carried by brackets 25 and 26 being securely bolted to these brackets as shown. The upper edge of the base board 15 is bolted or otherwise suitably secured to brackets 27 and 28. The brackets 25, 26, 27 and 28 are adjustably mounted upon parallel posts or pipes 29 and 30, being adapted to be clamped in any desired position along these 60 pipes, whereby the height of the base board 15 is readily adjustable. This particular mounting of the base board 15 is immaterial as the base board may be mounted in any other desired manner to meet various conditions of installation.

65 The switch blades 3—4 and 5—6, which switch blades are pivoted upon the bolts 8 and 12 respectively, are held together at their outer ends by means of spring washers 31—31 and 32—32 respectively, thru which spring washers a uniform spring pressure is maintained upon the blades 3—4 and 5—6 over substantially the entire contacting area to hold the blades firmly and uniformly against the opposite sides of the terminals 20 and 21 when the switch is closed. Heretofore in employing a single pair of spring washers in this manner it has been necessary to slot the terminal lugs to receive the binding bolt when the switch is closed, thereby decreasing the contacting surface relative to the size of the switch often materially.

70 Attempts to avoid slotting of the terminals have resulted in various constructions, probably the most common of which is the provision of a pair of spring washers adjacent the upper and lower edges respectively of the terminal, the clamping bolts thereby clearing the opposite edges of the terminal. I have observed that this construction is less desirable than the construction herein illustrated, the tendency of the blades towards spreading between the binding or 75

clamping bolts resulting in imperfect contact, the imperfection of which contact increases with the capacity of the switch.

I provide for clamping the spring washers 31-31 and 32-32 against the opposite sides of the blades 3-4 and 5-6 respectively in substantially the same relative positions as the spring washers 9-10 and 13-14 without slotting or otherwise altering the terminals 20 or 21. I accomplish this by the provision of a pair of clamping pieces or plates 34 and 35 in connection with each of the upper terminals of the switch. As shown in Figure 3, each of the clamping pieces 34 and 35 is provided with an inwardly projecting aligning stud 36 which aligning studs 36 engage in suitable openings provided substantially axially thru the spring washers 32-32. Axial recesses 20 may be provided instead of the axial openings shown—particularly in heavy capacity switches—as the co-operation of the studs 36 with suitable axial recesses would serve to align the spring washers 32-32 in a vertical plane equally as well. The clamping pieces 34 and 35 and consequently the spring washers 32-32 are securely clamped in place—obviously maintaining a uniform spring pressure upon the blades 5 and 6 over substantially the entire contacting area—by means of a plurality of bolts 37, the shanks of which bolts clear the upper and lower edges respectively of the terminal 21. The clamping pieces or plates 34 and 35 and the bolts 37 together form a frame between which the spring washers force the blades towards each other. It will now be apparent that I have provided means for holding the blades securely and uniformly against the opposite sides of the terminal 21, the uniform spring pressure maintained over substantially the entire contacting area being adjustable by means of the bolts 37. This spring pressure is distributed substantially uniformly over the contact surface of the blades against the terminal because it is applied substantially centrally of the contact and no appreciable bending stress on the blades results.

Although it is to be understood that I do not intend to be limited to a locking switch, I have provided an improved locking mechanism particularly adapted for use in connection with the above described switch when a locking switch is desired.

The upper edges of the upper switch terminals 20 and 21 are provided with notches 40 (Figure 1) in which the lower end of the T-shaped locking bolts 41 engage, one of these locking bolts being arranged between each pair of switch blades 3-4 and 5-6 respectively. The lower end of the locking bolt operating member 42 is bifurcated to provide two vertical portions 43 and 44. These vertical portions 43 and 44 are scarfed

as is also the upper end of the T-shaped locking bolt 41, these co-operating scarfed ends forming overlapping connections arranged between each pair of switch blades; sufficient clearance being provided so that the blades will be floating and in no case bound or clamped at this point.

The lower edges of the vertical portions 43 and 44 of the locking bolt operating members 42 are provided with lugs 45 (Figure 1) which lugs 45 engage beneath the enlarged heads of the T-shaped locking bolts 41.

The locking bolt operating members 42 and the locking bolts 41 are guided for reciprocating movement by bolts 46, the shanks of which bolts extend thru registering slots provided in the locking bolt operating members 42 and in the locking bolts 41.

As shown in Figure 3, compression springs 47 mounted in suitable slots provided in the locking bolts 41 are confined between one end of these slots and the transverse pins 48 extending thru the opposite ends of the slots and secured in the switch blades. Obviously the springs 47 tend to retain the lower ends of the locking bolts 41 in the notches 40 provided in the upper edges of the upper switch terminals.

It will now be apparent that a pull with a suitable switch hook inserted in the ring 50 carried by the locking bolt operating member 42 will move this member and consequently the locking bolt 41, thru the lugs 45 longitudinally sufficiently to clear the upper edge of the switch terminal. The springs 47 are compressed simultaneously with this upward movement of the locking bolts 41 so that when the switch blades 8 and 12 into the open position the locking bolts will be forced back into their normal position. When the switch is again closed these locking bolts will be sprung into the notches 40 to securely lock the same in the closed position.

It will now be apparent that I have provided a switch of improved construction involving a minimum number of parts; independent terminal lugs and the like being dispensed with.

The features of a locking mechanism in connection with a floating blade disconnecting switch and the arrangement for clamping the spring washers to maintain a uniform spring pressure upon the blades over substantially the entire contacting area without slotting or otherwise altering the terminals of the switch are highly important aspects of the present invention.

While I have described my invention in connection with the details of a particular embodiment, I do not intend thereby to limit the invention to such details as I am aware

and contemplate that modifications and changes may be made without departing from the invention which is set out in the appended claims.

5. I claim:

1. In combination, a pair of stationary switch terminals, a pair of floating blades for connecting said switch terminals, spring means for retaining substantially the entire 10 contacting areas of said floating blades against the sides of said switch terminals, locking mechanism between said floating blades and a lock releasing member extending beyond the ends of said blades.
15. 2. In combination, a pair of stationary switch terminals, a pair of floating blades for connecting said switch terminals, spring means for retaining substantially the entire 20 contacting areas of said floating blades against the sides of said switch terminals, a locking bolt for engaging one of said switch terminals, said locking bolt being movable longitudinally relative to said switch blades, a lock releasing member cooperating with 25 said locking bolt and extending beyond the ends of said floating blades, said lock releasing member having an aperture therein engageable by a switch operating hook.
30. 3. In a locking switch, a pair of parallel floating switch blades, locking mechanism between said floating blades, said blades being full floating relative to said locking mechanism, a lock releasing member extending beyond the ends of said floating blades 35 and having an aperture therein engageable by a switch operating hook.
40. 4. In combination, a pair of switch terminals comprising a plurality of bus bars, a pair of floating blades for connecting said switch terminals, a locking bolt for engaging one of said switch terminals, said locking bolt being movable longitudinally relative to said switch blades, a lock releasing member co-operating with said locking bolt and movable angularly relative to said switch blades, said lock releasing member extending beyond the ends of the blades and being engageable by a switch operating hook.
45. 5. In combination, a pair of switch terminals, a pair of switch blades pivoted on opposite sides of one of said switch terminals, spring means for pressing said blades against said one terminal, spring means for pressing said blades against the other terminal, said second spring means being disposed substantially centrally relative to the area of contact of said blades with said second terminal, clamping pieces for said second spring means, and bolts arranged adjacent the opposite edges of said second terminal and co-operating with said clamping pieces to press said blades against said terminals.
55. 6. In combination, a pair of switch terminals, a pair of switch blades pivoted on
- opposite sides of one of said switch terminals, spring means for pressing said blades against said one terminal, spring means for pressing said blades against the other terminal, said second spring means being disposed substantially centrally relative to the area of contact of said blades with said second terminal, clamping pieces for said second spring means, means arranged adjacent the opposite edges of said second terminal and co-operating with said clamping pieces to press said blades against said terminal, and a locking mechanism arranged between said blades, said locking mechanism allowing a full floating action of said blades.
7. In combination, a pair of stationary switch terminals, a pair of switch blades pivoted upon one of said switch terminals, spring means substantially centrally disposed relative to the contacting area of said blades with the other terminal, and clamping means for maintaining a substantially uniform spring pressure upon the blades, said clamping means being independent of the formation of said second terminal.
8. In combination, a pair of contacts comprising a hinge contact and a free contact, a pair of blades lying one on each side of the contact, a pivot pin passing thru the inner ends of the blades and the hinge contact, spring means for yieldingly holding said ends flat against the hinge contact, a plurality of bolts passing loosely thru the blades on each side of the region where the blades engage the free contact, plates or clamps held loosely on the outside of the blades by said bolts, and spring means lying between said plates and the blades.
9. In combination, a pair of contacts comprising a hinge contact and a free contact, a pair of blades lying one on each side of the contact, a pivot pin passing thru the inner ends of the blades and the hinge contact, spring means for yieldingly holding said ends flat against the hinge contact, a plurality of bolts passing loosely thru the blades on each side of the region where the blades engage the free contact, plates or clamps held loosely on the outside of the blades by said bolts, spring means lying between said plates and the blades, a locking bolt lying between the outer ends of the blades and adapted to engage the free contact, and means for controlling said locking bolt and for moving the switch blades.
10. In combination, a plurality of pairs of switch contacts, grouped pairs of blades yieldingly embracing pairs of contacts between them, said blades being hinged in pairs to one group of said contacts and adapted to engage with the others of said contacts on the outer sides thereof, a plurality of locking bolts lying between the outer ends of the pairs of blades for each contact, and a common means for control-

ling the locking bolts in unison and for moving all of said switch blades to open and closed positions.

11. In a switch, a free switch contact, a pair of blades adapted to have contact with the outer surfaces of said switch contact, a spring member lying outside of each blade, a relatively stiff yoke member for each blade engaging the corresponding spring member and bolts passing through both blades outside the area of engagement of blade and contact, said bolts holding the ends of the yoke a predetermined distance away from each other to maintain a spring pressure upon the blades when they are in contact with the switch contact.

12. In combination, a plural unit switch, comprising two or more hinge contacts and two or more free contacts, each hinge contact having a pair of flat blades lying on the outer face thereof, a hinge pin for the pair of blades, means between the outer ends of the blades of each unit for spacing the blades apart, said means comprising a locking bolt for locking the pairs of blades against movement, and common means for operating all the pairs of blades in unison, said means controlling the locking means of each pair.

13. In combination, a plural unit switch comprising two or more hinge contacts and two or more free contacts, each hinge contact having a pair of flat blades lying on the outer face thereof, a hinge pin for the pair of blades, means between the outer ends of the blades of each unit for spacing the blades apart, said means comprising a locking bolt for locking the pair of blades against movement, spring means for the outer ends of each pair of blades for holding them yieldably against the outer sides of the free contacts, and common means for operating all the pairs of blades in unison, said means controlling the locking means of each pair.

14. In a switch and board construction, a supporting board, bus bars in back of the board, short sections of bus bar projecting in parallel through the board and forming switch studs in pairs, each pair comprising a hinge stud and a free stud, a switch arm for each pair of studs, each arm comprising a pair of blades lying on the outsides of the corresponding studs, spring means for holding each pair of blades in full floating contact with its pair of studs, locking means for each switch arm lying between the blades of each pair, and common means controlling all the locks of the arms and serving to open and close the arms in unison.

15. In a switch and board construction, a supporting board, bus bars in back of the board, short sections of bus bar projecting in parallel through the board and forming switch studs in pairs, each pair

comprising a hinge stud and a free stud, a switch arm for each pair of studs, each arm comprising a pair of blades lying on the outsides of the corresponding studs, spring means for holding each pair of blades in full floating contact with its pair of studs, locking means for each switch arm lying between the blades of each pair, and common means controlling all the locks of the arms and serving to open and close the arms in unison, the sections of bus bar comprising the hinge studs being all clamped together electrically at the rear of the board and the sections of bus bar comprising the free studs being all clamped together electrically at the rear of the board.

16. In combination, rigid terminals and flexible switch blades, said blades being positioned to be held towards each other and against the outer sides of said terminals by the magnetic field of the current, and locking means positioned between the outer ends of the blades outside the effect of the magnetic field and adapted to be moved into closer engagement by mechanical separation of the terminals under the forces generated by the magnetic field of the current.

17. In combination, spaced blades, a pivot contact between the inner ends thereof, a rigid free contact finger entering between the free ends of the blades, the ends of said blades projecting past said finger, and a locking device housed between the projecting ends of the blades and engaging said finger to lock the switch in closed position, said locking device having an operating eye extending beyond the free end of the blades, and connected equally to both blades for operating the switch.

18. In combination, spaced floating blades, a rigid pivot contact between the inner ends thereof, a rigid free contact finger entering between the free ends of the blades, a locking bolt housed between the ends of the blades beyond said free contact, means normally holding said bolt in locking engagement with said finger, and a release member movable in the plane of movement of the blade projecting from between said blades for moving said bolt out of locking position, said member being connected to both blades for exerting an equal effort upon the same.

19. In combination a rigid contact finger, a rigid pivot contact, spaced flexible blades pivoted on the pivot member and adapted to straddle said finger and project beyond the same, means for yieldingly holding the blade against said pivot member and on said contact finger and locking means housed between the projecting free ends of the blades beyond the contact finger and connected to both blades for exerting the same effort upon them upon closing the switch or on holding the same locked.

20. In combination, a rigid contact finger,

spaced floating blades adapted to straddle and resiliently grip said finger, the free ends of the blades projecting past said finger, a locking bolt housed between said projecting free ends, and a lock-operating and switch-operating member pivoted on both blades and projecting beyond said free ends.

21. In combination, spaced floating switch blades, a locking bolt for locking said switch 10 in closed position, an operating member pivoted on both blades and projecting from between said blades and movable in the plane of the movement of the blades through a predetermined path with respect thereto, 15 said path extending an equal distance on either side from a normal locking position, means normally positioning said operating member in an intermediate position and said bolt in locking position, and connections for 20 withdrawing said bolt upon movement of said operating member in either direction from its normal intermediate position, said operating member serving as the sole means for operating said blades.

22. In combination, spaced floating switch blades, a lock bolt between said blades, a single free contact finger between them, and a movable lock and switch operating eye pivoted equally on the free ends of said 30 blades beyond the free contact finger, said eye operating through said pivot to actuate the blades and having a portion thereof lying between said free ends for operating the lock bolt.

23. In combination, a pair of spaced floating switch blades, a single free contact finger between them, a movable lock and switch operating eye pivoted on both said blades and projecting beyond the ends of the blades, 40 said eye having a portion lying between the free ends of the blades beyond the free contact finger, and locking means lying between said blades and engaging the outer edge of the free contact finger, said locking means being controlled by movement of said eye 45 when the eye is actuated to open the switch.

24. In combination, a free contact, spaced floating switch blades, means for holding said blades yieldingly against said contact, 50 a movable blade operating finger projecting beyond the ends of said blades, a pintle for said finger passing through the ends of the blades and locking means actuated by said finger and guided on said pintle, said locking means engaging the outer edge of said 55 free contact.

25. In combination, spaced switch blades, a free contact, means for causing the blades yieldingly to engage the sides of said contact, a movable blade operating finger projecting between said blades, a pintle for said finger passing through the ends of said blades beyond said free contact, said finger being engageable by a pulling hook, and 65 locking means engaging the outer edge of

the free contact and having a portion actuated by the finger to open the lock upon movement of the finger to either side from neutral position in opening or closing the switch.

26. In combination, a hinged contact, a free contact, a pair of floating blades pivoted on said hinged contact and adapted to engage the sides of the free contact, means for causing the blades yieldingly to hold said contacts, a locking bolt guided between the free ends of the blades beyond the free contact for engaging the outer edge of the free contact, said bolt having a T-shaped operating portion at its outer end and a bolt 80 and switch operating member having an open eye pivoted upon the end of the blades, and extending clear of the ends of the blades, said member having a portion co-operating with said T-shaped portion of the bolt for 85 slidably withdrawing the bolt upon movement of the eye upon either side of a neutral position.

27. In combination, floating blades, spring means for holding said blades in firm contact with a terminal finger, tension means for loading said spring means, and locking mechanism guided in its movement by said tension means.

28. In combination, floating blades, tension bolts passing through said blades, and a longitudinally slideable locking element guided by said blades and bolts.

29. In combination, floating blades, bolts passing through said blades, certain of said bolts operating in tension to limit separation of said blades, and locking mechanism supported and guided entirely by said blades and bolts.

30. In combination, terminals, floating blades pivoted on one terminal, tension bolts carried by said blades and lying beside the edge of the free terminal remote from the pivot terminal when the switch is closed, and a locking element between said blades 110 guided between said bolts to engage the free terminal.

31. In combination, terminals, floating blades pivoted on one terminal, tension bolts carried by said blades and lying beside the edge of the free terminal when the switch is closed, and a locking element guided between said bolts to engage the free terminal.

32. In combination, a pivot terminal, floating blades thereon, a free terminal, tension bolts lying beside the remote edge of the free terminal when the switch is closed, the ends of said blades projecting beyond said bolts, a single bolt at the blade ends, and a locking element slotted to slide on said single bolt, the nose of said element sliding between said first mentioned bolts.

33. In combination, a pivot terminal, floating blades thereon, a free terminal, tension bolts lying beside the remote edge of

the free terminal when the switch is closed, the ends of said blades projecting beyond said bolts, a single bolt at the blade ends, a locking element slotted to slide on said single bolt, the nose of said element sliding between said first mentioned bolts, and a pulling eye pivoted on said single bolt and actuating said locking element.

34. In combination, a pair of contacts, a double blade switch arm pivoted on the hinge contact and adapted to lie wholly outside of and embrace the free contact, a locking device between the outer ends of the blades beyond the free contact, and an operating eye pulling equally upon the blades and controlling the locking bolt.

35. In a switch, a free switch contact, a pair of blades adapted to have contact with the outer surfaces of said switch contact, means for yieldingly pressing the blades against the sides of the contact, said means comprising a yoke lying outside of each blade and extending across the contact and bolts passing through both blades outside the area of engagement of blades and contact and taking up the reaction of the yokes against the blades.

36. In combination, a pair of flat sided switch terminals comprising a hinge terminal and a contact finger terminal, a pair of blades lying outside of said terminals, mechanical means for pressing the blades against the sides of the terminals, said blades being adapted to be pressed towards each other and against the sides of the terminals by the magnetic forces of current flowing through the blades, the ends of the blades extending out beyond the contact ter-

minal and being free of current flow, a locking device lying loosely between said ends and being adapted to engage a shoulder on the adjacent edge of the contact terminal, the magnetic forces tending to spread the terminals also tending to force the lock and shoulder more firmly into engagement.

37. In combination, a hinge terminal member, a contact terminal member, a pair of blades spaced apart and hinged on said first member and adapted to engage the second member, locking means carried by the blades beyond the contact member, said means comprising a detent having a central locking position and operating means actuated upon movement in the plane of the switch either to open or to close the switch for releasing said detent.

38. In a switch, a pair of blades adapted to embrace a contact between them, a bolt passing loosely through said blades on each side of the contact and yokes having their ends engaged by said bolts and their central portions pressed against the blades for yieldingly pressing the blades upon the contact.

39. In combination, a pair of blades adapted to embrace a contact between them, a bolt passing loosely through said blades on each side of said contact and yokes having their ends engaged by said bolts for pressing the blades against said contact, said yokes having inwardly projecting studs with spring washers held by said studs against the blades substantially centrally of the area of engagement of the blades with the contacts.

In witness whereof I hereunto subscribe my name this 8th day of April, A. D. 1919.

ERNEST H. JACOBS.
